ORGAN PIPE ASSEMBLY

Charles W. McManis, Kansas City, Kans.

Application December 8, 1947, Serial No. 790,332

6 Claims. (Cl. 84—331)

1

This invention relates to new and useful improvements in an organ pipe assembly, and has as its principal object the provision of a simpler, more easily manufactured pipe providing greater ease and speed of tonal regulation than is possible in the ordinary organ pipe.

In traditional pipe organ construction, each pipe consists principally of three parts, a conical tubular foot adapted to receive air at its smaller end from a windchest, a tubular pipe or resonator secured to the larger end of the foot and having a mouth formed therein at said juncture, and a partition known as a languid separating the foot from the resonator and having a slit formed therethrough adapted to direct a sheet of air against the upper lip of said mouth to produce a tone.

An object of this invention is the provision of an organ pipe assembly wherein the resonators are structurally divorced from the foot and languid equivalents, said resonators being secured adjustably to a specially constructed chestblock which performs the foot functions for an entire bank of pipes.

Another object is the provision of an organ pipe assembly comprising a chestblock carried on the windchest of an organ and adapted to support a plurality of resonators or pipes releasably and adjustably secured thereto, and individual air passages formed through said chestblock for each of said resonators adapted to direct air from said windchest to said resonator, and a languid secured to said chestblock within each of said resonators and adapted to form in conjunction with said passage an air slit adapted to direct a sheet of air against the lip of said resonator.

Other objects are simplicity and economy of construction, flexibility of adjustment and adaptability to utilize commercial tubing, which is available in all the necessary graduations of size, without the use of conical tubes, and without welding or soldering.

With these objects in view, as well as other objects which will appear in the course of the specification, reference will be had to the drawing, wherein:

Figure 1 is a fragmentary front elevation of a bank of organ pipes, showing a pipe assembly embodying the present invention.

Fig. 2 is an enlarged fragmentary vertical section taken on line II—II of Fig. 1.

Fig. 3 is a fragmentary horizontal section taken on line III—III of Fig. 2.

Like reference numerals apply to similar parts throughout the several views, and the numeral 4 applies to a fragmentary showing of an organ

2

windchest having a topboard 6. Air is delivered under pressure to said chest by blower means not shown. An aperture 8 is formed through the topboard for each organ pipe, the apertures for each bank of pipes being disposed in a line extending transversely across the windchest.

A chestblock 10 preferably having the form of an elongated plank of wood or other suitable material, is secured to topboard 6 by any suitable means such as screws 12. A recess 14 is formed in the lower surface of chestblock 10 directly above each aperture 8, said recess being disposed adjacent the rearward edge of the chestblock. Each recess 14 is interconnected by a forwardly extending passage 16 with a recess 18 formed in the forward edge of the chestblock, said last named recess opening at both the forward and upper surfaces of the chestblock. A slit 20 is formed between the upper edge of a cap plate 22 fixed to the forward surface of the chestblock and extending across recess 18, and the forward edge of a planar languid 24 fixed to the upper surface of the chestblock, said slit being adapted to direct a sheet of air 25 upwardly from the chestblock.

A tubular pipe 26 commonly known as a resonator, is supported on chestblock 10 above each slit 20. At its lower end each resonator has a flattened portion 28 at its forward side 30 said flattened portion sloping inwardly as shown in Fig. 2. Said flattened portion is slit horizontally at a point above the lower end of the pipe, and the resultant strip of metal is cut vertically at its midpoint, the end portions of said strip then being bent outwardly to form ears 30. The space vacated by said ears forms the pipe mouth 32. The upper lip 34 of said mouth may be bevelled to a sharp edge as shown in Fig. 2.

The sheet of air passing upwardly from slit 20 crosses mouth 32 and breaks across lip 34 thereof, thus setting up a vibration in the air column carried in resonator pipe 26 to produce a tone. Ears 30 serve to confine the sheet of air as it crosses mouth 32. If larger ears extending above and below mouth 32 are desired, ears 30 may be used as anchorages for said larger ears. Tonal quality of the pipe is affected by the conformation and relative positioning of cap 22 and languid 24. Since these members are releasably secured to the chestblock by screws or in some other manner readily lending itself to adjustment, voicing of the pipe may be accomplished much more easily and faster than in ordinary pipes requiring soldering or welding of the parts.

Each pipe is provided at its lower end with

transversely extending flanges 36 as best shown in Fig. 3, said flanges adapted to be clampingly secured to chestblock 10 by large headed screws 38, the head of each of said screws being adapted to engage clampingly the adjacent flanges 36 of consecutive pipes 26. The lower end of each pipe is dipped in a liquid plastic which dries to a spongy consistency to form a plastic gasket 40 providing an air-tight seal between the pipe and the chestblock. With screws 38 loosened, pipe 26 may be slid forwardly or rearwardly to position lip 34 properly with respect to the sheet of air from slit 20. When the proper adjustment has been obtained, positioning pins 42 may be fixed in chestblock 10 to project through holes provided therefor in flanges 36. Thereafter the pipe may be removed simply by loosening screws 38 and lifting flanges 36 from pins 42, and may be replaced accurately in position by fitting said flanges over said pins.

A volume control valve 44 is carried on a vertical screw 46 threaded through the top of chestblock 10 to the rear of each pipe, said valve being adapted to cover and regulate the amount of air passing through aperture 8. An operating valve 48 is carried within windchest 4 in conjunction with each aperture 8, and is adapted to open or close said aperture. Said valve is normally urged toward its closed position against the lower surface of windchest topboard 6 by a spring 50, and is opened by the windchest pressure exerted downwardly on diaphragm 52 whenever the pressure beneath said diaphragm is exhausted. The faces of valves 44 and 48 may be provided with felt covering 54 having leather facings 56 to insure quiet, efficient closure. Valves 48 are operable from the keyboard console of the organ by means not shown.

Thus it is apparent that a simple, economical organ pipe assembly has been produced which may be easily and rapidly adjusted, which requires no relatively expensive foot portion, which requires no soldering or welding, and which may be simply manufactured from commercially available tubing.

What I claim as new and desire to protect by Letters Patent is:

1. An organ pipe assembly comprising a chestblock mounted on the windchest of an organ and having a plurality of individual air passages formed therethrough, said air passages each communicating at one end with said windchest and formed at its opposite end to present a slit adapted to direct a sheet of air outwardly, and a tubular resonator carried by said chestblock above each of said slits, each of said resonators having an open mouth adjacent said slit and a lip adjacent said mouth over which said sheet of air breaks to produce a tone.

2. An organ pipe assembly comprising a chestblock mounted on the windchest of an organ and having a plurality of individual air passages formed therethrough, said air passages each communicating at one end with said windchest, members adjustably secured to the outer surface of said chestblock to partially close the open opposite end of each of said air passages to form a slit adapted to direct a sheet of air upwardly, and a tubular resonator carried by said chestblock above each of said slits, each of said resonators having an open mouth adjacent said slit and a lip adjacent said mouth upon which said sheet of air impinges to produce a tone.

3. An organ pipe assembly comprising a chestblock fixed to the windchest of an organ and

having a plurality of individual air passages formed therethrough, each of said air passages communicating at one end with said windchest, and opening at its opposite end at the forward and upper surfaces of said chestblock, a cap secured to the forward surface of said chestblock to cover the forward opening of said air passage, a languid secured to the upper surface of said chestblock, the forward edge of said languid being spaced apart from the upper edge of said cap to form a slit for directing a sheet of air upwardly, and a tubular resonator carried by said chestblock above each of said slits, each of said resonators having an open mouth adjacent said slit and a lip adjacent said mouth upon which said sheet of air impinges to produce a tone.

4. An organ pipe assembly comprising a chestblock mounted on the windchest of an organ and having a plurality of individual air passages formed therethrough, said air passages each communicating at one end with said windchest and forming at its opposite end a discharge slit for directing a sheet of air outwardly, a tubular resonator mounted on said chestblock above each of said slits, each of said resonators having an open mouth adjacent said slit and a lip adjacent said mouth and parallel to said slit, upon which said sheet of air impinges to produce a tone, and means for adjustably moving said resonator transversely to said slit to secure proper cutting of said sheet of air across said lip.

5. An organ pipe assembly comprising a chestblock supported on the windchest of an organ and having a plurality of individual air passages formed therethrough, said air passages each communicating at one end with said windchest and forming at its opposite end a discharge slit for directing a sheet of air outwardly, a tubular resonator mounted on said chestblock above each of said slits, each of said resonators having an open mouth adjacent said slit and a lip adjacent said mouth and parallel to said slit, upon which said sheet of air impinges to produce a tone, flanges turned outwardly from the lower edge of said resonator on a diameter parallel to the plane of said mouth, and screws secured in said chestblock adjacent said flanges, the heads of said screws releasably securing said flanges to said chestblock, thereby permitting the adjustment of said resonator transversely to said slit to secure proper cutting of said sheet of air across said lip.

6. An organ pipe assembly comprising a chestblock mounted on the windchest of an organ and having an air passage formed therethrough communicating at one end with said windchest and forming at its opposite end a discharge slit for directing a sheet of air outwardly, and a tubular resonator adjustably mounted on said chestblock, said resonator having a mouth adjacent said slit, across which mouth said sheet of air passes to impinge on the upper lip thereof to produce a tone.
